US0D1036186S

(12) **United States Design Patent** (10) **Patent No.:** **US D1,036,186 S**
(45) **Date of Patent:** **** Jul. 23, 2024**

(54) **OVEN**

(71) Applicant: **SHARKNINJA OPERATING LLC**,
Needham, MA (US)

(72) Inventors: **Joshua D. Anthony**, North Billerica,
MA (US); **Nicholas Varjabedian**,
Middleboro, MA (US); **Dan
Kestenbaum**, Brookline, MA (US)

(73) Assignee: **SharkNinja Operating, LLC**,
Needham, MA (US)

(**) Term: **15 Years**

(21) Appl. No.: **29/740,196**

(22) Filed: **Jul. 1, 2020**

Related U.S. Application Data

(63) Continuation of application No. 29/694,047, filed on
Jun. 6, 2019, now Pat. No. Des. 977,297.

CLAIM

The ornamental design for an oven, as shown and described.

DESCRIPTION

FIG. 1 is a perspective view of an oven;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the figures illustrate features of the oven
that form no part of the claimed design.

1 Claim, 6 Drawing Sheets
